(57) **CLAIM**

We claim, the ornamental design for a painter's tool caddy, as shown and described.

DESCRIPTION

FIG. 1 is a front isometric view of the painter's tool caddy showing our new design with a drawer and a tray in exploded view, with cover and pair of doors in open position, storage space with pegboard, sleeves, and pair of front legs and back wheels;

FIG. 2 is a rear elevational view showing cover and handle in closed position, thereof;

FIG. 3 is a side view, showing cover and doors in open position, and handle in open position thereof;

FIG. 4 is an opposite side view, showing doors in open position, and handle in open position thereof;

FIG. 5 is a bottom plan view, showing cover in open position, doors in closed position, and handle in closed position, thereof; and,

FIG. 6 is a front isometric view, showing cover in open position, and doors and drawer in closed position, thereof.
